UNITED STATES PATENT OFFICE.

JOSEPH MATHY, OF HOT SPRINGS, ARKANSAS.

METALLIC CRATE.

No. 874,782.

Specification of Letters Patent.

Patented Dec. 24, 1907.

Application filed April 11, 1907. Serial No. 367,569.

To all whom it may concern:

Be it known that I, JOSEPH MATHY, of Hot Springs, in the county of Garland and State of Arkansas, have invented certain new and useful Improvements in Metallic Crates; and I hereby declare that the following is a full, clear, and exact description thereof, reference being had to the accompanying drawings, which form part of this specification.

This invention is an improvement in metallic crates for carrying bottles containing fluids, such as milk, beer and the like, and its object is to provide a strong durable crate the parts of which can be practically stamped out of sheet-metal, in sections, and thence readily assembled and securely united together, forming a stiff strong durable box. The crates furthermore are made with tapered sides so that they are smaller at top than at bottom, and the bottoms of the crates are inset, so that one crate will fit over and upon another, the bottom of a superposed crate closing the top of the underlying crate, and the latter preventing lateral displacement of the former.

The crates are to be watertight, so that they can contain ice to refrigerate their contents, and if any bottle breaks the fluid is not spilled into the wagon; further the crates are preferably provided with grates which separate the bottles, and are preferably made removable so that the crates can be easily cleaned. The crates are also provided with novel covers—to protect their contents—and which are so constructed as not to interfere with the nesting of the crates.

One feature of the invention is the peculiar joint between the bottom and side walls of the crate, the joint being so made as to form a depending flange which is of larger internal diameter than the top of the crate and which affords a broad bearing surface to support the crate on the floor, and dispenses with the necessity of any bottom reinforcing band. Furthermore the crate is formed with rounded corners, so that it can be more readily cleansed, will be more convenient to handle, and will not be as liable to injure other objects or crates when tossed about, as such crates are subject to rough usage and handling.

I will now describe the crate and grate as illustrated in the accompanying drawings, and refer to the claims for statement of the novel features for which protection is desired.

In said drawings—Figure 1 is a top plan view of the complete crate with cover partly broken away. Fig. 2 is an end view thereof partly broken away, and partly in section to illustrate how the crates are “nested”, and how the covers are applied. Fig. 3 is a detail vertical section of the crate, cover and grate. Fig. 4 is an enlarged section through the bottom joint of the crate. Fig. 5 is a perspective view of the grate removed. Fig. 6 is a sectional view of a slight modification of the grate. Fig. 7 is a perspective view illustrating one of the joints and the support disconnected. Figs. 8, 9 and 10 are details illustrating the construction of the grate joints.

The side and end walls of the crate are preferably constructed of two similar opposed metal plates 1, which are bent approximately into U-shape, their extremities being connected by interlocking joints as at 1^a, at about the central lines of the ends of the crate, this enables the side and end walls to be formed practically integral, and to be stamped by dies from sheets of suitable metal, preferably heavy sheet-iron. The side and end walls are tapered inwardly from top to bottom as shown, so that the top of the crate is smaller in diameter than its bottom.

Around the upper end or top of the crate is applied a stiffening metal band 2, and the upper edges of the walls of the crate are turned over the upper edge of said band as at 1^b; and said band may be further fastened permanently in place by rivets 2^a as shown.

The lower edges of the walls of the crate are formed with a depending flange 3, which is offset from the walls, as indicated at 3^a, so that the flange 3 is of larger diameter than the base diameter of the walls, and the flange 3 has an outwardly turned foot-portion 3^b which is adapted to lie flat upon the surface on which the flange rests.

The bottom 4 of the crate is stamped by suitable dies from a sheet of metal, and is adapted to fit closely within the flange 3 and up against the offset 3^a. The bottom is stamped with a depending flange 4^a, adapted to fit closely within and against flange 3, and the lower part of flange 4^a is turned horizontally outward under the horizontal foot-portion 3^b of flange 3, and is then bent upward and over the part 3^b, as at 4^b, as shown more clearly in Fig. 4. By this construction the bottom 4 is fitted closely in the crate, and the parts 3, 4^a, form a depending supporting

flange of double thickness supporting the bottom above the surface on which the crate rests, and the parts 4^b, 3^b, 4^c, form a base-bearing-flange of triple thickness supporting the crate upon the surface on which it rests. This triple-thickness bearing-flange extends entirely around the crate, and projects outwardly beyond the supporting flange;—and I purposely make the bearing-flange portions 10 3^b, 4^b, noticeably wide, so that the part 4^b in contact with the surface upon which the crate rests is of much greater area than would be afforded if the part 4^b turned directly upward against the outer side of flange 15 3. By this construction I retain the full thickness of metal in the part 4^b to withstand the wear and strain to which the bearing-flange is subjected, and this part 4^b is not strained or weakened as it would be by 20 bending it directly upward against flange 3, consequently its strength is retained, and the broad wearing surface afforded by the part 4^b will resist wear indefinitely long, and by providing this broad bearing-flange I am 25 enabled to dispense with any reinforcing metal band around the base of the crate.

In order to close the top of crate and protect or conceal its contents, it may be provided with a cover 1^e, as shown. This cover 30 is preferably stamped out of sheet metal and is slightly smaller than the internal area of the top of the crate, so that it can be placed therein as shown, and it is provided with an upstanding peripheral flange 1^f which is adapted to fit pretty closely within the upper end of the crate; and flange 1^f is provided at top with an outwardly projecting return bend forming a supporting flange 1^g by which the cover is supported upon the upper edge of the crate 40 as shown.

The cover may be removably fastened in position by suitable means; I prefer to use the catches 1^h attached to flat spring plates 1ⁱ which are secured to the flange 1^f of the cover, 45 which flange is perforated for the passage of catches 1^h.

When the cover is put in place, the end of catch 1^h springs into an aperture 2^h made in the top band 2 of the crate, as shown, and 50 thus securely locks the cover in place. Preferably two such catches are used, one at each end of the crate cover. Rings 1^k can be attached to the inner ends of the catches 1^h as shown to facilitate their disengagement 55 from the crate. The cover thus constructed will not interfere with the boxes nesting one upon the other—see Fig. 2, and will protect the contents of the crate from exposure.

The crate is provided with handles 5 riveted 60 to its ends as shown, or otherwise suitably attached thereto. It is also provided with a grating which may be permanently riveted therein as indicated in Fig. 1, or removably placed therein as indicated in Fig. 2.

65 The grating is preferably constructed of

two series of intersecting metal straps 6 and 7. The straps 6 are wider than straps 7, and are provided at the intersecting points with slots 6^a; for the passage of straps 7, said slots being preferably formed by partly punching 70 out tongues 6^b in the straps 6, as shown in Fig. 9, so that the straps 7 can be readily slipped therethrough. After the straps 7 are in place, the tongues 6^b can be forced back, as indicated in Fig. 10, so as to bind tightly 75 against the strap 7 and lock the latter in place. If desired the straps 7 may be provided with indentations 7^a at their intersecting points, so that the tongues can be forced 80 into these indentations and positively lock 80 the straps at such points as shown in Fig. 10. This construction affords a very strong durable and cheap grating.

If it is desired to have the grating fixed in the crate, the ends of the straps 6 and 7 may be riveted to the side walls of the crate as shown at 6^e, 7^e, Fig. 1. When the grate is to be removable, I provide it with supports 8, preferably formed of U-shaped metal bands, having their upper ends slotted to embrace straps 7, and then turned over the upper edges of straps 6, as shown in Figs. 5, 7. This construction makes a very strong and efficient support, secures the supports rigidly to the grating, and enables it to be 95 readily removed and replaced, and supports the grate at a proper height above the bottom of the crate. The removable grates may be provided with an inclosing band 9 riveted to the ends of the straps 6 and 7 as indicated in 100 Figs. 2, 5. Or such band can be dispensed with and the extremities of the straps 6 and 7 rounded, as indicated in Fig. 6.

From the foregoing description it will be seen that the crate is simple in construction, capable of standing hard usage, easily cleansed, and will nest nicely; and the grate is simple strong and efficient.

Preferably after the crates are put together they are galvanized, so that the galvanizing deposits seals the joints hermetically, and much better results are obtained than would be possible if the plates were galvanized before the parts were made or assembled. The grates are also preferably galvanized after 110 they are formed, for like reason.

Having described my invention what I claim as new and desire to secure by Letters Patent is:

1. The herein described metallic crate, having its side walls formed with an offset depending flange provided with a horizontally projecting foot-portion, an inset bottom piece provided with a depending flange closely fitting the depending flange of the 120 side walls and having a horizontal flange extending under and lapped over and upon the said foot-portion, the vertical portion of said flanges forming a double wall supporting 125 flange upholding the bottom above the sur- 130

face upon which the crate rests and the horizontal portions of said flanges forming a triple walled bearing-flange having a broad bearing surface on its underside, substantially 5 as described.

2. The herein described metallic crate comprising two opposite metal portions bent into approximately U-shape and united at their ends to form the side and end walls of 10 the crate, said walls being formed with an offset depending flange at their base, said depending flange having a horizontally extending foot-portion; and a bottom piece stamped from sheet metal having a depending 15 flange fitted closely within the offset flange of the walls, and having a horizontally extending portion underlying the said foot-portion, and turned over and lapped upon said foot-portion and forming therewith a 20 bearing flange broad on its under surface and extending entirely around the base of the crate, the walls of the crate being inclined inwardly from bottom to top so that the top of one crate is adapted to fit within the supporting 25 flanges of a like crate, substantially as described.

3. The herein described metallic crate having its side and end walls formed of two opposite metal portions bent into approximately 30 U-shape, the crate having rounded corners, and said side walls being inclined so that the upper end of the crate is smaller than the base portion, said walls being formed with an offset depending base flange having 35 a horizontally extending foot-portion; a bottom piece having a depending flange fitted closely within the offset flange of the walls, and having a horizontally extending portion underlying and turned over and lapped upon 40 said foot-portion, the vertical portions of the said flanges forming a double walled supporting flange and the said foot-portion inclosing flanges forming a double walled bearing 45 flange, said bearing flange being broad on its under surface and extending entirely around the base of the crate, the top of one crate being adapted to fit within the supporting flange of a like crate, substantially as described.

50 4. In combination with a crate, a grating therefor, comprising a series of intersecting

straps arranged edgewise, one set of said straps having tongued slots through which the other set of straps are passed, the free ends of the tongues being forced back to lock 55 the straps in the slots.

5. A grating composed of a plurality of parallel straps arranged edgewise and having tongued slots formed by partially punching tongues therefrom, and a plurality of intersecting straps also arranged edgewise and extending through the slots in the first series of straps, the second set of straps having indentations at the intersecting points, and the free ends of the tongues being forced into 60 65 said indentations to lock the straps.

6. A grating comprising two sets of intersecting metal straps arranged edgewise, one set of said straps having tongued slots through which the other set of straps are 70 passed, the free end of the tongues locking the straps in the slots, and an inclosing band surrounding the grating and attached to the exterior ends of the straps.

7. A grating composed of a series of parallel straps arranged edgewise and having slots formed by partially punching tongues therefrom, a second series of straps also arranged edgewise and extending through the slots in the first series of straps, the 80 second set of straps having indentations at their intersecting points, the free ends of the tongues being forced into said indentations to lock the straps, and an inclosing band surrounding the grating and attached to the 85 exterior ends of the straps.

8. In combination with a crate, a grating therefor, comprising a series of intersecting straps, one set of said straps having tongued slots through which the other set of straps 90 are passed, the tongues being forced back to lock the straps in the slots, and U-shaped supports attached to the grate to uphold it within the crate.

In testimony that I claim the foregoing 95 as my own, I affix my signature in presence of two witnesses.

JOSEPH MATHY.
